UNITED STATES PATENT OFFICE

118,611

DESIGN FOR A BICYCLE FRAME

John R. Alexander, Paris, Tex.

Application November 13, 1939, Serial No. 88,243

Term of patent 14 years

To all whom it may concern:

Be it known that I, John R. Alexander, a citizen of the United States and a resident of Paris, in the county of Lamar and State of Texas, have invented a new, original, and ornamental Design for Bicycle Frames, of which the following is a specification.

Reference is had to the accompanying drawing, forming part thereof, in which:

Figure 1 is a perspective view of a bicycle frame, showing my new design.

Figure 2 is an inverted plan view of said bicycle frame.

Figure 3 is a front elevation of the bicycle frame.

I claim:

The ornamental design for a bicycle frame, as shown.

JOHN R. ALEXANDER.
